UNITED STATES PATENT OFFICE.

DAVID F. SHOPE, OF PORTLAND, OREGON, ASSIGNOR TO THE SHOPE BRICK CO., OF PORTLAND, OREGON.

BRICKMAKING-MACHINE.

1,306,977.

Specification of Letters Patent. Patented June 17, 1919.

Application filed June 13, 1917. Serial No. 174,511.

To all whom it may concern:

Be it known that I, DAVID F. SHOPE, a citizen of the United States, residing in the city of Portland, county of Multnomah, and 5 State of Oregon, have invented certain new and useful Improvements in Brickmaking-Machines, of which the following is a specification.

My invention relates to brick making machines of the character shown and described in Letters Patent Number 965,027, issued to me July 19, 1910. This machine, like the one referred to, is adapted to receive a plastic substance, such as cement, or a cement mixture, and is capable of manipulation for the purpose of effectively and speedily tamping and molding said substance into bricks.

One of the principal objects of the present invention is to provide in a machine of the 10 character referred to adjustable form members adapted, when in place, to form a series of molds into which the plastic material is placed, together with improved means for tamping such material firmly into said forms, the side and front form members being removable from the formed bricks, whereby to leave the same in spaced relationship upon a removable pallet, which can be lifted bodily from the machine.

Another object of the present invention 15 is to provide a removable front form member, which can be so removed from the front ends of the formed bricks, as with a wiping movement, whereby to avoid danger of disturbing, or breaking away, any of the material of which the brick is formed, and leaving the ends of the bricks exposed for further finishing treatment.

In order to more clearly explain my invention 20 I have illustrated the same in the accompanying drawings, which I will now describe.

Figure 1 is a top plan view of a brick making machine embodying my invention;

Fig. 2 is a front end view thereof, with parts shown in section;

Fig. 3 is a side view thereof, with parts shown in section;

Fig. 4 is a front end view of the molds, 25 with a guard board in place to protect the top surface of the bricks while the ends thereof are being treated;

Fig. 5 is a detail;

Fig. 6 shows top and front views of a re- 30 movable pallet, which forms the bottom of

the mold forms when in place in the machine; and

Fig. 7 is a sectional view taken on line 7—7 of Fig. 1.

Referring now in detail to the drawings 35 my invention, as here embodied, comprises a table structure having the legs 1—1, suitable brace bars 2—2, top end members 3—3, and top side members 4—4, said top side members 4—4, being extended rearwardly 40 so as to project beyond the table legs, as clearly shown in Figs. 1 and 3.

A plurality of side form plates 5—5, are 45 adjustably secured together on screw threaded bolts 6—6, with adjustment nuts 7—7, on 50 each bolt at the opposite sides of each plate 5—5, as clearly shown in Figs. 1 and 2, said bolts being attached at their opposite ends to side members 8—8, the lower edges of 55 which, at their rear ends, move upon rollers 9—9, and the upper edges of which have bearing thereon rollers 10—10, mounted in brackets 11—11, secured to the opposite sides 60 of the machine, as will be clear from the drawings. Mounted on the outer sides of 65 said side members 8, are racks 12—12, adapted to mesh with gears 13—13, mounted at the 70 opposite sides of the machine on a shaft 14, provided on its outer ends with cranks 75 15—15, whereby said racks 12—12, said side 80 members 8—8, and said spaced form plates 5—5, can be moved longitudinally together 85 rearwardly until the forward ends of said side plates 5—5, are drawn through a cross back plate 16, provided with vertical slots 90 through which said side plates 5—5 slide. Said side plates 5—5 are drawn through 95 said back plate 16, until their ends are substantially flush with the front face of said back plate 16, in a manner which will be 100 readily understood from Figs. 1 and 3.

Detachably mounted across the front of the machine is a supporting pallet 17, shown in top and front edge views in Fig. 6, said pallets having end pieces 18—18 on their under sides on which to stand said pallets, and a metal plate covering 19, said metal plate covering being somewhat shorter than the pallet body 17, and being slightly wider, as clearly shown in the drawings. When said 105 pallets are removed with bricks thereon they can be set one upon the other. Said pallet 17 is put in place, as shown in sectional view in Fig. 3, while the side plates 5—5, are in 110 their back, or withdrawn position, so that

as said side plates are moved forwardly their lower edges rest firmly upon the top surface of said pallet. Detachably mounted on the front of said machine is a front end plate 20, 5 provided with a handle 21, said front plate being held in place against the front edge of the pallet 17, and the front ends of the spaced side plates 5—5, by means of an angle plate 22, mounted upon the inner face there- 10 of at one end, the projecting angle thereof having a hole therethrough adapted to pass over a pin 23, in the forward end of the side plate 8, as clearly seen at the upper left hand corner of Fig. 1, and also shown in dotted 15 lines of Fig. 2. The opposite end of said front plate 20, is provided with a latch hook 24, pivotally connected, as at 25, Fig. 5, to an end cleat 26, on said front plate 20. Said latch hook 24 hooks over a pin 27, in the 20 outer side of the side member 8. Said latch hook 24, is provided with a handle 28, by means of which it can be conveniently raised so as to permit the removal of said front plate 20, by a sliding longitudinal movement 25 to the left, as shown in Fig. 2, to detach the angle plate 22, from the pin 23, at the opposite side of the machine. This sliding movement of said front plate against the front ends of the brick forms tends to smooth the 30 ends of the bricks and to release the board therefrom before the side members 5—5, are withdrawn, thus avoiding possibility of the material sticking to the front board, or falling away from the ends of the formed bricks. 35 Said front plate is removed with a wiping movement.

A tamping member comprising two side members 29—29, are pivotally mounted on a cross shaft 30, the opposite ends of which are 40 pivotally supported in side brackets 31, mounted upon the opposite sides of the machine, as shown, with a spacing sleeve 32, mounted upon said shaft between the side members 29—29, as will be clear from Fig. 1. 45 Said side members are bent inwardly to approaching angles, as at 29^a—29^a, at their rear ends, and have adjustably attached thereto a balancing weight 33. Said side members are braced with an X-brace 34. Pivotally 50 mounted between the forward ends of said side members 29—29, is a tamping head 35, having a series of downwardly depending tamping portions 36, adapted to fit, one between each pair of the side members 5—5, 55 when said tamping head and said frame members 29—29, are swung downwardly, as by means of a handle extended between the ends of the side members 29—29, said handle constituting a bar 37, with a pipe 38, mount- 60 ed thereon, as clearly shown in the drawings.

The weight 33, at the rear end of tamping frame members 29—29, serves as a balance for the tamping head 35, so as to make it comparatively easy to raise said tamping head by hand, and at the same time add to

the tamping force of the tamping head as it is drawn downwardly, in the tamping operation.

Stop members, as 39, are mounted at the rear ends of the top side members 4—4, and 70 operate as a stop for the side members 8—8, which carry the side plates 5—5. Two stop pins 8^a—8^a, are mounted on the inner faces of the side members 8—8 to stop the forward movement of said side plates at the 75 right place. Two guard plates, or covers, as 40—40, are mounted at the opposite sides of the machine over the rack 12, and the gear 13, to prevent sand and cement from getting into the mechanism, and interfering with the 80 operation thereof.

A pivoted front guard plate, as 41, is mounted upon side arms 42—42, pivoted to the side of the guards, or covers 40—40, as clearly shown in Figs. 3 and 4, whereby said 85 guard plate 41, can be swung over to the position shown in broken lines in Fig. 3, just above the front end plate 20. This guard plate 41, serves as a protection for the top surfaces of the formed bricks after the 90 front end plate 20 has been removed and it is desired to apply to the front ends of the formed brick a further coating or treatment for finishing the same. Said guard plate 41 is provided with a handle 41^a, and 95 also with a supporting piece 41^b, adapted to rest upon the upper edge of one of the side plates 5, when said guard plate is turned back into the position shown in Fig. 3.

Referring to Fig. 1, the upper right hand corner thereof, there is shown a spring member 43, provided with a spring yoke 44, adapted to act as a stop to be engaged by the rear end of one of the tamping frame members 29^a, to hold said tamping frame 105 in its raised position, as indicated in broken lines in Fig. 3. The engaging portion of the spring yoke is formed, as indicated in the detailed, sectional view, Fig. 7, so as to permit the member 29^a, to flex it backwardly, 110 as said member 29^a moves downwardly, whereupon said spring yoke 24, engages the upper edge of said member 29^a and holds said tamping frame 29 in its raised position until it is pulled downwardly. Thus said 115 tamping frame is automatically and yieldingly held in its raised position, out of the way, after the tamping of the material has been completed, and at the same time is within convenient reach of the operator. 120

I am aware that changes in details can be made in my invention without departing from the spirit thereof, and I do not, therefore, limit said invention to the specific construction here shown for purposes of 125 illustration, except as I may be limited by the hereto appended claims.

I claim:

1. In a brick making machine, in combination, a pallet, side plates spaced apart, 130

a back plate, a removable front plate mounted against the front ends of said side plates, and a guard plate adapted to be moved to a position above the ends of said side plates 5 when said front plate is removed, for the purpose described.

2. In a brick making machine, in combination, a pallet, side plates spaced apart, a back plate, a removable front plate mounted against the front ends of said side plates, and a guard plate pivotally connected to 10

said machine and adapted to be moved to a position above the ends of said side plates when said front plate is removed, for the purpose described. 15

Signed at Portland, Multnomah county, Oregon, this 6th day of June, 1917.

DAVID F. SHOPE.

In presence of:

I. N. GRIFFIN,
J. C. STEENG.
